Specification for Design.

Patented Aug. 29, 1922.

Application filed November 19, 1920. Serial No. 425,272. Term of patent $3\frac{1}{2}$ years.

To all whom it may concern:

Be it known that I, JOSEPH W. WUNSCH, a citizen of the United States, residing at Brooklyn, in the county of Kings and State of New York, have invented a new, original, and ornamental Design for a Pair of Book Ends, of which the following is a specification, reference being had to the accompanying drawing, forming a part thereof.

The figure is a perspective view of my book ends, showing my design.

I claim:

The ornamental design for a pair of book ends, as shown.

JOSEPH W. WUNSCH.
